DOOR LOCK

William V. Schweitzer, New Britain, Conn., assignor to The American Hardware Corporation, New Britain, Conn., a corporation of Connecticut

Application October 8, 1956, Serial No. 614,730

3 Claims. (Cl. 70—216)

This invention relates to a door lock and more particularly to a door lock of the so-called "unit" type which is primarily intended for use on the entrance doors of stores and the like.

The primary object of this invention is to provide a unit lock having inner and outer knobs which may be simultaneously locked and unlocked by key operated means contained in both of said knobs, and in which said knobs may be simultaneously locked by the key operated means in either one of the knobs and simultaneously unlocked by the key operated means contained in the opposite knob.

A further object of this invention is to provide a mechanism which will function in the manner above described and is simple in construction.

Another object of this invention is to provide a mechanism which is adapted for use with the parts of the lock common to all other functions.

Further objects and advantages of this invention will be more clearly understood from the following description and the accompanying drawings in which:

Fig. 1 is a plan view of a unit lock embodying the present invention.

Fig. 2 is a fragmentary plan view of said lock, partially in central horizontal section, illustrating the lock mechanism in normal unlocked condition.

Fig. 3 is an isometric view illustrating particular elements of the lock mechanism and the relative positions which they occupy in the lock.

Fig. 4 is a fragmentary front view of the lock, partially in central vertical section, further illustrating the lock mechanism.

Fig. 5 is a view similar to Fig. 4, but further illustrating the construction of the lock.

Fig. 6 is a sectional end view taken on line 6—6 of Fig. 4.

Figs. 7, 8 and 9 are sectional end views of the lock taken, respectively, on lines 7—7, 8—8 and 9—9 of Fig. 4.

Fig. 10 is a fragmentary sectional front view of the lock illustrating the condition of the lock mechanism when both the inner and the outer knobs are dogged against operation.

Fig. 11 is a fragmentary plan view further illustrating the lock mechanism when in dogged condition.

In this application I have chosen to illustrate my invention as embodied in the basic unit lock housing originally disclosed in my copending application Serial No. 498,525, filed April 1, 1955, and now Patent No. 2,821,849, issued February 4, 1958 but it will be readily understood that said invention is applicable to other types of door locks without departing from the spirit thereof.

Throughout the drawings I have illustrated only those parts of the lock which are associated with the present invention since the basic characteristics of a unit lock are well known to those familiar with the art and the construction and operation of those portions of the lock

2

which are not shown in detail are conventional and will be readily understood.

Referring now to Fig. 1 of the drawings, the numeral 5 indicates the housing of the lock which is adapted to carry the entire lock mechanism and is received in a notch 6 extending into the edge of a door 7 in the manner characteristic of all unit locks. The housing 5 is secured in said notch by inner and outer escutcheon plates 8 and 9 which are clamped against the opposite faces of the door by screws 10 which extend through the inner escutcheon plate 8 and are threaded to the outer plate 9. The housing 5 has a front wall 11 which is disposed flush with the edge of the door and elongated side walls 12—12 which extend rearwardly therefrom. A tubular knob shank bearing sleeve 13 extends transversely through said side walls adjacent the rear end of the housing and projects through openings in the inner and outer escutcheon plates. The bearing sleeve is secured to the housing by pins 14—14 which extend thereunto from a tie-bar 15 that is attached to the side walls 12—12. The portion of the bearing sleeve 13 between the side walls of the housing contains diametrically opposed clearance openings 16—16 which are located symmetrically with respect to the vertical axis of the sleeve and from the outer edges of which there extend diametrically opposed locking notches 17—17 which are located centrally of the clearance openings. Similar notches also extend from the inner sides of the clearance openings since the bearing sleeve of the lock is a standard part which is used in all functions, but in the present embodiment the inner locking notches are not used.

The housing 5 carries a latch bolt 18 which is pivotally mounted thereon by a pin 19 and extends through an opening in the front wall 11. The latch bolt is connected to a conventional retractor 20 which extends longitudinally of the housing and includes a yoke portion 20a which straddles the bearing sleeve 13 and has laterally extending arms 20b—20b whose forward faces provide rollback platforms 20c—20c. A further detailed description of the retractor is not believed necessary since its construction is conventional and it is well understood that the retractor and the latch bolt are biased into normal position, as illustrated throughout the drawing, by a conventional compression spring. The lock mechanism is protected from dirt and other foreign matter by a dust cover 5a which is disposed over the open sides of the housing.

The knob shank bearing sleeve 13 rotatably supports inner and outer separate tubular knob shanks 21 and 22 which are secured, respectively, to inner and outer knobs 23 and 24. Said knob shanks are retained against axial movement by suitable locking keys 25—25, as clearly described in my copending application Serial No. 577,509, filed April 11, 1956, and have their inner ends in close proximity. The inner end of the inner knob shank 21 contains a pair of diametrically opposed, horizontally extending slots 26—26, and the adjacent end of the outer knob shank 22 contains a pair of similarly disposed slots 27—27 which are normally aligned with the slots 26—26. The inner end of the outer shank also contains a pair of diametrically opposed vertically extending slots 28—28. It will be noted that the slots 28—28 extend to approximately the end of the locking notches 17—17 and are normally aligned therewith.

In order for the lock to function in the prescribed manner, relative rotation of the inner and the outer knobs must be prevented. This could conceivably be accomplished by the use of a single, one-piece, knob shank instead of the separate shanks 21 and 22. However, since the shanks 21 and 22 are standard parts adapted for use in locks having other functions, their use in the pres-

ent structure is much preferred and relative rotation therebetween is prevented by a U-shaped coupling member 29 which connects said shanks together. Said coupling member includes a circular central portion 29a which is adapted to fit within the bore of the inner knob shank and is provided with an axial hole 29b. A pair of diametrically opposed arms 29c—29c extend radially and then perpendicularly from said central portion 29a and are adapted to fit within the slots 26—26 and 27—27 in the inner and the outer knob shanks, respectively, to thereby prevent relative rotation of said shanks. It will thus be understood that the inner and the outer knob shanks rotate simultaneously upon rotation of either the inner or the outer knob.

The retractor of the lock is actuated by a single rollback 30 which is non-rotatably carried by the outer knob shank, and, as best shown in Fig. 7, includes a circular hub portion 30a that is disposed within the bore of the outer knob shank and has diametrically opposed arms 30b—30b extending therefrom through the slots 28—28 and through the clearance openings 16—16 to a position overlying the rollback platforms 29c—29c on the retractor. When either the inner or the outer knob is rotated in either direction, the inner and the outer knob shanks will be rotated simultaneously to thereby rotate the rollback 30 which will urge the retractor 20 and the latch bolt 18 into retracted position.

The rollback 30 is adapted to slide axially in the outer knob shank from a normal position, as illustrated in Figs. 1 through 5, to a dogging position, as shown in Figs. 10 and 11, wherein the arms 30b—30b thereof are disposed in the locking notches 17—17. In this position, rotation of the rollback is prevented and the outer knob shank is thereby dogged against operation. Since the inner knob shank is connected to the outer knob shank through the coupling member 29, rotation of the inner knob shank is also prevented, and it will be understood that upon movement of the rollback into dogging position both the inner and the outer knob shanks are simultaneously dogged against operation.

In order to move the rollback into and out of dogging position, I have provided a spindle 31 which is disposed axially of the knob shanks and extends through an axial opening 30c in the rollback and through the opening 29a in the coupling member 29. The said spindle is adapted to rotate relatively to the rollback, but is secured against axial movement with respect thereto by suitable locking rings 32—32.

The inner knob 23 contains a conventional cylinder lock 33 having a rotatable key-plug 34 which projects through an opening in the wall of the knob. A tubular cam 35 is secured to the inner end of the key-plug 34 by a pin 36 and is mounted for rotation in the inner knob shank 21. The inner end of the spindle 31 extends into the cam 35 and is both rotatable and axially slideable relatively thereto. The cam is provided with a cam slot 37 which receives a cam follower pin 38 extending radially from the spindle 31.

A similar cylinder lock 39 is carried by the outer knob 24 and said cylinder lock also contains a rotatable key-plug 40 which projects through an opening in the wall of the knob. A tubular driver 41 is secured to the inner end of the key-plug 40 by a pin 42 and is mounted for rotation in the outer knob shank 22. The outer end of the spindle 31 extends into the driver 41 and is also both rotatable and axially slideable relatively thereto. The driver has a semi-circular extension 43 having abutment surfaces 44 and 44a at its opposite ends which are adapted to engage with a pin 45 extending radially from the spindle which provide a lost motion connection permitting 180° relative rotation between the spindle and the driver. It will be understood that the cam 35 and the driver 41 are normally prevented from rotating relatively to their respective knob shanks by the pin tumblers contained within the cylinder locks.

The coupling member 29 is retained in fixed position relatively to the knob shanks and the spindle by a compression spring 46 in the inner knob shank which surrounds the spindle and is disposed between said coupling member and the end of the cam 35 and urges the arms of the coupling member into the slots in the outer knob shank.

The above described mechanism permits simultaneous dogging or undogging of the inner and the outer knobs of the lock from either side of the door.

If it is desired to lock the door from the inside, the proper key is inserted into the key plug 34 projecting from the inner knob and said plug is turned 360° in a counterclockwise direction which causes a similar movement of the cam 35. It will be noted from Figs. 2 and 4 through 6 that the spindle 31 can rotate from normal position for 180° in a counterclockwise direction relatively to the driver 41 or until the pin 45 projecting from the spindle engages the abutment surface 44a thereon so that the spindle will rotate with the cam during 180° of its movement. After the pin 41 engages the abutment surface 44a, however, further rotation of the spindle is prevented and the cam 35 will rotate relatively thereto for 180° to cam the spindle and the rollback axially toward the outer knob and shift the arms of the rollback into the locking notches 17—17 as illustrated in Figs. 10 and 11. In this position, rotation of both the inner and the outer knob shanks is prevented.

The inner and the outer knobs may be undogged from the inner side of the door by rotating the cam 350° in a clockwise direction which will cause a movement of the spindle and the rollback in reverse of that above described and will return the mechanism to the position shown in Fig. 2.

If desired, the knobs may be undogged from the outer side of the door by rotating the driver 41 with a suitable key for 360° in a clockwise direction from the position shown in Figs. 10 and 11. The driver will rotate relatively to the spindle for 180°, but during the remaining 180° of rotation, the driver will rotate the spindle relatively to the then stationary cam 35 to thereby cause axial movement of the spindle toward the inner knob and shifting of the rollback out of the locking notches 17—17.

My improved mechanism also permits dogging and undogging of the knobs from the outer side of the door by merely rotating the driver in the proper directions to cause rotation of the spindle 31 relatively to the stationary cam member 35, which results in axial movement of the spindle and the rollback into and out of dogging position in a manner which will be readily understood from the above description.

It will thus be seen, that my invention provides a mechanism for so-called "store-door" locks which is much less complicated and less expensive to produce than mechanisms having a similar function heretofore available.

I claim:

1. A door lock comprising a housing, a retractor for a latch bolt movable in said housing, separate inner and outer tubular knob shanks mounted to rotate in said housing and each having a knob secured thereto, the inner ends of said shanks having opposed pairs of slots extending longitudinally thereinto, a coupling member having a central portion disposed within one of said shanks and a pair of opposed arms extending therefrom adapted to be received in said slots and preventing relative rotation of said shanks, rollback means associated with at least one of said shanks for actuating said retractor upon rotation of said knob shanks by either of said knobs, dogging means movable into interengagement with one of said shanks and said housing to thereby prevent rotation of both of said shanks by either of said knobs, and means operable from at least one of said knobs for shifting said dogging means into and out of dogging position.

2. A door lock comprising a housing having a recess therein, a retractor for a latch bolt movable in said housing, separate inner and outer tubular knob shanks mounted to rotate in said housing and each having a knob secured thereto, each of said shanks having a pair of slots extending longitudinally into its inner end which are alignable with the slots in the inner end of the opposite shank, a U-shaped coupling member having a circular central portion fitting within one of said shanks and a pair of arms extending from said central portion into said slots and preventing relative rotation of said knob shanks, a rollback member non-rotatably connected to one of said shanks and adapted to actuate said retractor upon rotation of either of said knobs, said rollback member being shiftable axially of its shank and having portions adapted to be received in said recess to thereby dog said shanks against rotation by either of said knobs, a rotatable and axially movable spindle member contained within said shanks and extending through openings in said coupling member and said rollback, means securing said rollback to said spindle member for axial movement therewith, a cylinder lock contained in each of said knobs, cam means controlled by the cylinder

lock in one of said knobs for moving said spindle and rollback into and out of dogging position, and driver means controlled by the cylinder lock in the other of said knobs adapted to rotate said spindle relatively to said cam means to cause movement of said spindle and the rollback into and out of dogging position.

3. In a door lock, a housing having separate inner and outer tubular knob shanks mounted to rotate therein, each of said shanks having a pair of slots in its inner end which are alignable with the slots in the inner end of the opposite shank, and a U-shaped coupling member including a circular central portion disposed within the inner end of one of said shanks and having a pair of arms extending therefrom into the slots in said knob shanks to prevent relative rotation thereof.
